UNITED STATES PATENT OFFICE.

EDWARD BARBER, OF HOPE VALLEY, RHODE ISLAND.

DESIGN FOR A SARCOPHAGUS.

SPECIFICATION forming part of Design No. 29,012, dated July 5, 1898.

Application filed April 26, 1898. Serial No. 678,913. Term of patent 14 years.

To all whom it may concern:

Be it known that I, EDWARD BARBER, of Hope Valley, in the county of Washington and State of Rhode Island, have invented a new and original Design for a Sarcophagus; and I do hereby declare that the following is a full, clear, and exact description thereof, reference being had to the accompanying drawing, which forms a part of this specification.

This design relates to a sarcophagus designed to be put in a grave to receive the casket instead of bricking up a place, as is often done, to inclose the coffin or casket and keep the earth from it. It is fully explained and illustrated in this specification and the accompanying drawing, which shows a perspective view of the sarcophagus.

My design for a sarcophagus consists of a

body in the shape of a plain parallelepiped, the side of which is about five times the length of its height and its breadth a little more than its height, and having a top slightly arched or raised in the middle and sloping down toward each side, the ridge of the arch running lengthwise of the sarcophagus.

Having thus described and illustrated my invention, what I claim as new, and desire to secure by Letters Patent, is—

The design for a sarcophagus for caskets herein shown and described.

In testimony whereof I have hereunto set my hand this 9th day of April, A. D. 1898.

EDWARD BARBER.

In presence of—

CHAS. N. RICHMOND,
BENJ. ARNOLD.
